UNITED STATES PATENT OFFICE.

ALFRED L. FLOOD, OF CHICAGO, ILLINOIS, ASSIGNOR OF ONE-HALF TO
WILLIAM L. WEBER, OF CHICAGO, ILLINOIS.

TILE.

SPECIFICATION forming part of Letters Patent No. 708,472, dated September 2, 1902.

Application filed March 3, 1902. Serial No. 96,390. (No model.)

To all whom it may concern:

Be it known that I, ALFRED L. FLOOD, a citizen of the United States, residing at Chicago, in the county of Cook and State of Illinois, 5 have invented a certain new and useful Improvement in Tiles, of which the following is a specification.

My invention relates to tiles for floors, walls, and other surfaces, and has for its object to 10 provide a new and improved tile of this description.

My invention is illustrated in the accompanying drawings, wherein—

Figure 1 is a view of a portion of a surface, 15 showing the tiles in position. Fig. 2 is a view of one of the circular tiles, and Fig. 3 is a view showing the other associated tile.

Like letters refer to like parts throughout the several figures.

20 One of the objects of my present invention is to provide a construction which will enlarge the adaptability and extend the usefulness of tiles of various kinds. In the laying of such tiles it is desirable to be able to produce ornamental effects by using various-shaped tiles and assembling them in proper relation, thus permitting the use of various borders, fields, &c.

As illustrated in Fig. 1, I have shown a series of dissimilar or different tiles connected together and embodying my invention. In the drawing a number of different-shaped tiles A B C D, &c., are used. It will be noted that these tiles are provided with recesses A' 35 and engaging or interlocking projections B', which fit into such recesses. The tiles A, for example, have a series of these recesses, and the tiles B have a series of projections B'. It will be noted that instead of one recess containing one projection such recess contains two different projections on different tiles, so that a part of two separate and different tiles project into any given recess. This feature gives the great adaptability to my invention 40 and permits the various-shaped tiles to be connected together to form a floor, wall, or other surface. It will be noted that in connection with tiles A and B the receiving-recesses are arcs of circles and the projections B' are substantially semicircles, and when the tiles are formed together the two projec-

tions B' of the adjacent tiles meet in the same recess. It is not necessary to have these projections and recesses circular, but they can be of any desired shape, and I have shown them rectangular in connection with some of the tiles. Many other shapes might be used; but in any event I desire to have parts of two different tiles contained in one receiving or interlocking recess.

In Fig. 2 I have shown a circular tile A cut away at four preferably equidistant points, so as to form the arc-engaging surface A'.

In Fig. 3 I have shown a tile B adapted to be associated with the tile A and provided with interlocking projections B', having curved or arc-engaging faces B² adapted to engage the faces A' of the associated tiles A.

It will be noted when the tiles A and B are used all of the engaging faces of the tile are curved and are preferably arcs of circles. The interlocking projections B' are parts of circles, and in the drawings they are shown as semicircles. It will further be seen that when the series of tiles A and B are assembled in their proper relation and the surface completed the tiles are interlocked, so as to be held in place.

In order to show how this form of tile adapts itself to borders and the like, I have shown it in connection with a number of differently-shaped tiles. The tiles C E, for example, have the corners cut away, so as to form the curved interlocking or engaging faces A'. Between the several sections of differently-shaped tiles are provided the connecting-tiles G H, which are provided with the interlocking projections I, as shown. It will thus be seen that I have here a construction which adapts itself readily to various conditions and to a great variety of uses, and thus facilitates the adaptation of tiles for floors, walls, and other surfaces.

The tiles may be made of elastic or non-elastic material; but I prefer to use some suitable elastic material—such, for example, as rubber or some compound thereof.

I claim—

1. A floor, wall or other surface composed of a series of tiles of different shapes or forms, one form consisting of a circular tile cut away at various points to provide circular recesses, the other having circular engaging faces pro-

ided with interlocking projections adapted to fit such circular recesses.

2. The combination with a series of circular tiles of a binding or interlocking tile 5 adapted to be interposed between the circular tiles and provided with interlocking projections which engage such circular tiles.

3. The combination of a series of surface-forming flat tiles with interlocking edges to 10 form when thus interlocked an extended flat surface, such interlock consisting of a curved recess in the edge of one of such tiles and curved projections on adjacent tiles, two of such projections lying in engagement with 15 each of said recesses.

4. A floor, wall or other surface made up of a series of dissimilar tiles, provided with

curved recesses of greater width at the mouth and curved interlocking projections, the curved projections adapted to fit into the 20 curved recesses, substantially as described.

5. A floor, wall or other surface made up of a series of tiles of various shapes, said tiles having their outer boundary interrupted by 25 projections and recesses, the faces of the projections adapted to engage the faces of the recesses, such engaging faces being arcs of circles and such recesses of greatest width at their mouths.

ALFRED L. FLOOD.
